[57] CLAIM

The ornamental design for a holder for golf balls and accessories, as shown and described.

DESCRIPTION

FIG. 1 is a perspective view of a holder embodying the design invention;

FIG. 2 is a front elevational view thereof;

FIG. 3 is a side elevational view thereof;

FIG. 4 is a top view thereof;

FIG. 5 is a rear view thereof; and,

FIG. 6 is a top view thereof.

The broken lines illustrating a pair of golf balls, a set of golf tees, a divot tool, a ball marker and a hook and loop patch are for illustrative purposes only and form no part of the claimed design.
